UNITED STATES PATENT OFFICE.

JOE FRAIDUS, OF NEWARK, NEW JERSEY, ASSIGNOR TO SAMUEL SCHNIPER, OF NEW YORK, N. Y.

MACHINE FOR MAKING RADIATOR-CORE SECTIONS.

Application filed July 8, 1920. Serial No. 394,685.

To all whom it may concern:

Be it known that I, JOE FRAIDUS, subject of the Government of Russia, and resident of the city of Newark, in the county of 5 Essex and State of New Jersey, have invented certain new and useful Improvements in Machines for Making Radiator-Core Sections, of which the following is a specification.

10 My invention relates to machines for shaping and bending sheet metal and has particular reference to machines for making the corrugated sheets used in radiator manufacture, for building up the cores of 15 radiators for automobiles, trucks, tractors, airplanes and the like.

One of the objects of this invention is to provide a machine which will produce sheet metal pieces in such a shape that they may 20 be properly and easily fitted together and joined to give proper liquid passages and spaces, and provide ample cooling surface for the liquid and ample radiating surface.

Another object is to provide a machine 25 of simple and low cost construction, having easily renewable parts and in which adjustments may readily be made to accommodate varying thickness of metal, and varying widths of sheets.

30 A further object is to provide a machine in which the parts may be readily changed to change the form of the finished sheet metal pieces.

Another object is to provide a machine 35 which will produce sheet metal pieces that when properly joined will give a radiator of pleasing appearance, and efficient design, suitable for the uses for which it is made.

Other objects will in part be obvious and 40 in part be pointed out hereinafter.

The invention accordingly consists in the features of construction, combinations of elements and arrangement of parts which will be exemplified in the construction hereinafter described and of which the scope of application will be indicated in the appended claims.

45 In the accompanying drawings, in which is shown one of various possible illustrative embodiments of this invention,

Figure 1 is a front elevation, partly in section, of a machine embodying the invention;

Fig. 2 is a side elevation thereof (partly

diagrammatic) viewed along line 2—2 of 55 Fig. 1;

Fig. 3 is a sectional view of the intermeshing corrugated rolls;

Fig. 4 is a perspective view of a section of a radiator through the center of the tubes, 60 showing the honeycomb arrangement;

Fig. 5 is a lengthwise sectional view through a set of the tubes;

Fig. 6 is a front view of the honeycomb section of the radiator showing a modified 65 form; and

Fig. 7 is a perspective view of the end of one sheet formed by the machine shown.

Referring in detail to the drawing, the frame of the machine comprises a base 10 70 having upright members 9, 9, each having a slot 8 for a purpose to be later described. On each upright is a lower angle piece 7 rigidly fixed to the upright by machine bolts or other desired means. An upper angle 75 piece 6 is fixed to each upright by machine bolts or screws such as 5 passing through slots 4, 4, in each angle piece 6 so that the same may be adjusted vertically within the limits of slots 4, 4 by the action of nuts 80 3, 3 and 3', 3' on the spacer rods 2, 2, which are fixed in the lower angle piece 7. Web members 1, 1 extend on the base between the uprights 9, 9 for purposes of strength.

Split pillow blocks 20, 20 are mounted on 85 lower angle pieces 7, 7 and similar split pillow blocks 30, 30 are mounted above the blocks 20, 20 on angle pieces 6, 6. The pillow blocks 20, 20 act as bearings for a shaft 19 which extends through slots 8, 8, and 90 90 on which a drive pulley 18 is mounted, a belt to deliver power to said pulley being shown in section at 17 (Fig. 1).

Mounted on the shaft 19 is a main corrugated roll 16 and two pairs of toothed 95 plates 15, 15' and 14, 14'. A pair of guide plates 13, 13' are mounted on the shaft and clamp against the outer toothed plates 14, 14', being secured to the main roll 16 by bolts 12 which extend through the plates 100 into threaded holes in the main roll 16. The entire assembly may thus be clamped together.

A nut 21 threaded on a reduced portion of the shaft 19 is adapted to act against 105 a collar 23 interposed between the nut and guide plate 13 to force the assembly against an integral collar 22 of the shaft and thus

fixes the position of the roll and toothed plates.

It will be noticed that the use of a collar 23 permits of the mounting of a longer assembly set of roll and plates on the shaft 19, if desired.

In pillow blocks 30 is a shaft 29 on which is another assembly similar to the lower assembly already described and comprising a main roll 26, an outer pair of toothed plates 24, 24' and an inner pair of toothed plates 25, 25', this assembly being held together by bolts 27 and positioned against integral collar 32 by means of a nut 31 and a collar 28. Vertical adjustment of the center to center distance between shafts 19 and 29 may be made by adjustment of upper angle pieces 6 holding the pillow blocks 30 by loosening bolts 5, 5, threading down nuts 3', 3', and threading on nuts 3, 3, then clamping bolts 5, 5 into position.

It will be noted that the guide plates 13, 13', within which the assembly is mounted are of sufficient diameter to overlap the upper assembly. In this way strips of metal fed into the rolls are guided by plates, 13, 13' between the rolls.

The upper assembly may also be lengthened when desired, in conjunction with a lengthened lower assembly, by the similar arrangement of collar 28 and nut 31 on shaft 29.

It will also be seen that the collar 32 on the upper shaft together with the collar 22 on the lower shaft positively position the members of the assembly with relation to each other, the upper collar 32 being of the thickness of the lower collar 22 plus the thickness of the guide plate 13'. In this way positive longitudinal alignment of the members of the assembly is assured, each member being of the width of its intermeshing member and the outer faces of the collars 22, 32 being equidistant from the reduced bearing portions of the shafts 19, and 29 respectively.

Referring now to the sectional view of the rolls in Fig. 3, the main rolls 16 and 26 have intermeshing corrugations of a ratchet shape with blunt jointing portions at the crests and depressions. This ratchet shape causes the center portion of the sheet metal plates to be bent as shown in Fig. 4 with each alternate face 33 wider than the adjacent intervening faces 34, the alternate faces 33' and 34' of the roll 16 and the alternate faces 33'' and 34'' of the roll 26 being of shape and width to correspond to the faces 33 and 34 respectively.

The outer toothed plates 14, 14' of the lower assembly and plates 24, 24' of the upper assembly intermesh respectively, plates 14 and 24 being shown in Fig. 3. These plates have teeth which in contour are substantially identical with the main roll corrugation but in one assembly project

slightly beyond the main roll corrugations as shown at 24 and in the other assembly are depressed a corresponding distance as shown at 14. The result of the action of these rolls is to press a groove into the strip of metal at each end bordering the edge of the sheet metal strip, shown in section at 35 and 35' Fig. 5. If two strips as a, b (Fig. 5) are properly placed together back to back, the projecting portion of the edge groove of one will fit against the projecting edge groove of the other and soldering the two together will hold their edges together and provide space between the main corrugated portions equal in width to double the projection distance. 80

The inner toothed plates 15, 15' of the lower assembly and 25, 25' of the upper assembly, intermesh respectively, 15 and 25 being shown in Fig. 3. These plates have contours parallel and coincident with the outer toothed plates except at the extreme crest and depression points, where they project, or re-enter, a slight distance so that depressions of small size are formed at the crest of each corrugation and projections at 90 the depression of each corrugation, giving portions spaced the length of the corrugation face, as shown at 36, 36' (Fig. 3) which co-operate so that the several plates may be assembled correctly and held from slipping 95 either transversely or longitudinally.

It will be apparent that when a plurality of these plates are assembled, water or fluid space will be provided as between a and b (Fig. 3) and air space will be provided on 100 the opposite side of each sheet from that adjacent the water or fluid to be cooled.

The shape of the air passages is shown in Fig. 4 being of essentially honeycomb nature but in this embodiment presenting a trapezoidal shape. The corrugated rolls and the toothed plates may of course be constructed so as to produce different shapes of radiator core sections as for example that of a square on edge as illustrated in Fig. 6. 110

It will thus be seen that there is provided apparatus in which the several objects of this invention are achieved and which is well adapted to meet the conditions of practical use.

As various possible embodiments might be made of the above invention and as various changes might be made in the embodiment above set forth, it is to be understood that all matter herein set forth or shown in the accompanying drawings is to be interpreted as illustrative and not in a limiting sense. 115

Having thus described my invention, I claim as new and desire to secure by Letters Patent:—

1. In a machine of the class described, a roll assembly comprising a main corrugating roll, a pair of depression forming plates adjacent said roll, one on either face, a pair of grooving plates adjacent said depression 130

forming plates, and means to hold said assembly together.

2. In a machine of the class described, a roll assembly comprising a roll and a plurality of plates attached thereto, a second roll assembly having elements intermeshing with the roll and plates of said first mentioned roll, and guide plates on the outer faces of

said first mentioned roll assembly, overlapping the outer elements of said second roll ¹⁰ assembly.

Signed at New York city, in the county of New York and State of New York this 15th day of March A. D., 1920.

JOE FRAIDUS.
